(57) **CLAIM**

The ornamental design for a light sensor, as shown and described.

DESCRIPTION

FIG. 1 is a front perspective view of a light sensor showing our new design.

FIG. 2 is a rear perspective view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and,

FIG. 8 is a right side elevational view thereof.

In the drawings, the broken lines depict portions of the light sensor that form no part of the claimed design.
